UNITED STATES PATENT OFFICE.

JOHN T. ROWLEY, OF PITTSBURGH, PENNSYLVANIA.

INGOT-MOLD.

1,351,346.

Specification of Letters Patent. Patented Aug. 31, 1920.

Application filed December 8, 1916. Serial No. 135,792.

To all whom it may concern:

Be it known that I, JOHN T. ROWLEY, a citizen of the United States, residing at Pittsburgh, in the county of Allegheny and State of Pennsylvania, have invented a new and useful Improvement in Ingot-Molds, of which the following is a specification.

My invention relates to improvements in molds for casting ingots or billets.

The object of my invention is to produce a simple and efficient mold by the use of which billets can be cast, and if desired, converted into bars of any considerable length without reheating. I accomplish this by means of the apparatus hereinafter more specifically described, reference being had to the accompanying drawing, forming part hereof, in which:

Figure 1 is an end elevation of my improved ingot casting apparatus.

Fig. 2 is a side elevation of the same, partly in section.

Figs. 3 and 4 are respectively cross sections on lines 5—5 and 6—6 of Fig. 2.

Fig. 5 is a transverse sectional view of the door, showing the means of water cooling the same.

Fig. 6 is a central section of the same.

Referring to said drawings, 1 is a frame constructed of heavy angle iron, in which the casting apparatus is supported. The said casting apparatus comprises a plurality of vertically disposed molds, each of which is formed of the movable sections A—B. The upper end of each of said molds is secured to the water jacketed neck piece 2. Sections A and B are each water jacketed in any usual manner, are provided with an inlet *a* and an outlet *b*, for the admission and discharge of water for the purpose of lowering the temperature of the metal charged into the said molds and at the same time cooling the molds. The neck or

cap piece is also provided with a water jacket for a like purpose and with an inlet and an outlet, *d* and *e* respectively. The lower end of the mold is closed by a door or bottom plate 3, which is likewise water cooled, having an interior chamber in which is let a conduit 4, the outer end of which is closed and through which a similar conduit 5 is inserted.

The said conduit 5 is for the purpose of

admitting water, as shown in Fig. 5, and 55 the conduit 4 discharges the same through a conduit 6.

The movable sections A—B of said mold are capable of being moved slightly from and toward each other, by means of the 60 toggle members D, which are connected by means of the vertically disposed link 7, the ends of which are connected to the lever members or links 8 and 9 respectively. The said toggle members D are pivotally mounted upon stub shafts 50 formed in connection with bases 51 which are secured to the sides of the sections of the mold. The said toggle members are operated by a transversely disposed member 10, which is secured to a vertically disposed shaft or rod 11. The upper end of said rod 11 is connected to a lever 12, the inner end of which is pivotally secured upon a boss or lug 13, secured to a frame, the opposite free end 70 terminating in an operating lever or rod 14. The member 10 terminates at its ends in downwardly extending yokes 15 which loosely receive the members 8 of the upper set of toggle links D, the ends of the yokes 15 being provided with screws 16 and 17 which are adjustable, the ends of the screws engaging the upper and lower edges of the toggle member 8 and the adjustment of the screws regulating the play or looseness between the yokes and the toggle members. The said rod 11 is in reality formed in two sections, the lower end of the upper section 75 terminating in a socket 18, and the upper end of the lower section terminating in the lower end of said socket 18.

A spring is mounted between said socket 18 and the bearing 19, the lower end of said bearing having a serrated or toothed surface 95 20, which is adapted to interlock with a similar surface on abutment 21, which is rigidly secured to the lower section of the rod 11.

A spring 22 under torsion is mounted 100 upon said rod 11, between said abutment and the boss or bearing 23, on the lower end of the mold. The door or bottom plate 3, is rigidly secured upon the lower end of said rod and is adapted to swing with the lower 105 section thereof whenever the said rod is moved downward, disengaging the clutch formed by the serrated surface on the bearing 19 and the abutment 21, carrying the

door downward and opening the lower end of the mold. The torsion of the spring 22 swings the door horizontally.

If it is desirable, a further downward movement of the rod 11 operates the toggle members D a slight distance, so as to relieve slightly the pressure of the mold upon the metal contained therein, if such operation is desirable; otherwise, the pressure of the spring H is sufficient to hold the two sections A—B closely together.

When it is desirable to convert the ingot into bars of considerable length, the operator by manipulating the lever 12 thus actuating the toggle members, opens the members A and B sufficient to permit the ingot to drop down and enter the bite of the rolls 24, the action of which upon the ingot converts the same into bars or billets of considerable length. A supplemental set of rolls 25 may be employed for still further reducing the bar or billet.

Having described my invention, what I claim and desire to secure by Letters Patent, is:

1. In a casting apparatus, the combination of a mold comprising two sections, the said sections being connected by toggle members, means to operate said toggle members, a water jacketed neck piece constituting the upper end of the mold sections adapted to receive the metal initially, the lower end of said mold sections being closed by a water jacketed door, and means to swing said door into open position simultaneously with the opening of the mold sections.
2. In a casting apparatus, the combination of a mold comprising two sections, the said sections being connected by toggle members, means to operate said toggle members, a neck piece constituting the upper end of the mold sections adapted to receive the metal initially, the lower end of said mold sections being closed by a door, and means to swing said door into open position simultaneously with the opening of the mold sections.
3. In a casting apparatus, the combination

of an upright mold divided longitudinally into complemental sections, a door normally closing the lower end of the mold, and means for simultaneously separating the mold sections and opening the door.

4. In a casting apparatus, the combination of a mold divided longitudinally into complemental sections, toggle members connecting the sections, a door at the bottom of the mold, and means for actuating the toggle members to separate the mold sections.

5. In a casting apparatus, the combination of a mold which is divided longitudinally into complemental sections, toggle members connecting the complemental sections, a door normally closing the lower end of the mold, and means for simultaneously actuating the toggle members to separate the mold sections and at the same time open the door.

6. In a casting apparatus, the combination of a mold which is divided longitudinally into complemental sections, a door closing the bottom of the mold, spring actuated means normally tending to open the door, a toggle connection between the complemental mold sections, and means for simultaneously operating the toggle members and releasing the door.

7. In a casting apparatus, the combination of a mold divided longitudinally into complemental sections, a laterally swinging door at the lower end of the mold, a spring normally tending to swing the door into an open position, detent means holding the door in a closed position, a toggle connection between the complemental mold sections, and means for simultaneously actuating the toggle connection and releasing the detent means to open the door.

In testimony whereof, I have hereunto signed my name in the presence of two subscribing witnesses.

JOHN T. ROWLEY.
